UNITED STATES PATENT OFFICE

GUSTAVE ANDERSON, OF BERLIN, NEW HAMPSHIRE, ASSIGNOR TO BROWN COMPANY,
OF BERLIN, NEW HAMPSHIRE, A CORPORATION OF MAINE

EXPANDING MANDREL

Application filed April 30, 1930. Serial No. 448,588.

This invention relates to an expanding mandrel adapted to be inserted in the interior of hollow bodies, such as tubes or the like, and to be expanded so as to grip the article firmly.

5 An object of the invention is to provide a structure which is not only efficient in operation, but which is light, strong and inexpensive.

10 For a more complete understanding of the invention, reference may be had to the disclosure thereof in the following description and on the drawing, of which,—

15 Figure 1 is an end elevation of a mandrel embodying the invention.

20 Figure 2 is a side elevation, a portion being broken away to show a section on the line 2—2 of Figure 1.

25 Figure 3 is a transverse section on the line 3—3 of Figure 2.

30 Figure 4 is a perspective view of one of the expanding pieces.

35 Figure 5 is a side elevation of an arbor suitable for use with the mandrel.

40 Referring to the drawing in detail, the mandrel may include a pair of end plates 10, which, as shown, are annular in shape if intended for holding a tubular object.

45 The outer diameter of the plates is sufficiently less than the inner diameter of the object to be held to permit the ready insertion of the mandrel into the object. These plates may be held in parallel relation by a number of longitudinal tie-rods 11 which may be secured at their ends to the respective plates by any de-

50 sired means such as riveting, spot welding, or a screw threaded connection. A number of expanding pieces 12 are assembled with the end plates before the latter are secured to the tie-rods 11. The expanding pieces may be of

55 generally rectangular shape, as shown in Figure 4, and are provided with a notch 13 at each end having a depth which may be substantially equal to the thickness of an end plate 10. On either side of the notch 13 are

60 lugs 14, 15. The end plates are provided with a series of inner radial slots 16 and outer radial slots 17, the inner and outer slots being arranged in pairs on common radii.

65 Between each pair of slots is left a neck or bridge 18 which enters the notch 13 when the

parts are assembled so that the lugs 14, 15 enter respectively the slots 16 and 17. The overall length of each expanding piece 12 may be equal to the distance between the outer faces of the two end plates 10, so as to make

55 the ends of the lugs 14, 15 substantially flush with the outer faces of the end plates, but the lugs 14, 15 may project beyond the end plates if desired.

60 The width of the expanding pieces 12 is somewhat greater than the width of the annulus 10, so that the inner edges of the expanding pieces 12 project within the inner circles of the end plates 10, as is shown in Figure 1, when the outer edges of the expanding pieces are flush with the outer circles

65 of the end plates. The slots 17 are preferably cut substantially equal to the cross section of the lugs 15 so that the outer edges of the pieces are flush with the outer circles of

70 the end plates 10. The slots 16 are also preferably shaped to fit the lugs 14 so that the inner edges of the expanding pieces 12 are flush with the inner circles of the end plates

75 10 when the lugs 14 are against the necks 18.

80 The outer edges of the expanding pieces may be provided with one or more notches 20, two such notches being illustrated in Figure 4. These notches are made sufficiently deep to receive a circular spring 21 which may be snapped into place and is adapted to

85 hold the expanding pieces 12 yieldingly in their inward position, as illustrated in Figures 1 and 3. The lower corners of the expanding pieces 12 are preferably rounded as

90 at 22 so as to ride easily on conical wedging pieces which enter the ends of the mandrel

95 for the purpose of expanding it.

100 A suitable arbor for use with this type of mandrel is illustrated in Figure 5. This arbor may comprise a pair of members 23 and 24 which are provided with opposed frusto-conical cam surfaces on which the lower corners 22 of the expanding pieces 12 may rest.

105 A standard 25 may be provided to support the mechanism, this standard having a quill 26 secured thereto, as by a set-screw 27, so that the quill is thereby held against rotation.

110 The member 24 may be keyed to the quill 26 as by a suitable spline 29. The mutually adjacent ends of the members 23 and

115 100

24 may be crenelated with inter-engaging fingers as at 28, the projections of one member fitting slidably into the recesses of the other member so that the two members are held against relative rotation, but are free to move axially toward and away from each other. The members 23 and 24 are hollow and are internally threaded with right and left hand threads respectively for engagement with the threaded end of a spindle 30, this spindle being rotatable by any suitable means such as a knurled finger wheel 31. Since the members 23 and 24 are both held against rotation, it is obvious that rotation of the spindle 30 will move the members toward or away from each other according to the direction of rotation of the spindle, the axial movement of the members being brought about by the right and left hand threads when the spindle 30 is rotated so as to cause the members 23, 24 to move toward each other. The wedging action of their frusto-conical faces results in the expanding pieces 12 being forced outwardly to grip the interior of a tube or other article which has been thrust upon the mandrel. When the spindle 30 is rotated in the opposite direction, the springs 21 draw the expanding pieces 12 inwardly to a position flush with the outer edges of the end plates so that the article which has been held by the mandrel can be removed therefrom. This mandrel is light, strong, and inexpensive, and not only holds the work firmly but also centers it accurately.

35 The mandrel illustrated on the drawing is shaped for holding hollow cylindrical objects such as tubes, but it is obvious that the external contour of the end plates may vary for use in holding objects having hollows of other shapes.

40 I claim:

1. An expanding mandrel comprising a pair of annular end plates, each said end plate having a series of radial slots extending outwardly from the inner edge thereof, there being a corresponding series of radial slots extending inwardly from the outer edge thereof, means for holding said end plates rigidly in a parallel coaxial relation with corresponding slots in alignment, a plurality of expanding pieces having outer edges normally flush with the outer edges of the end plates and having a pair of lugs on each end thereof projecting into a pair of slots in said end plates, and means for resiliently holding the expanding pieces in their inner position.
2. An expanding mandrel comprising a pair of annular plates having a series of radial notches extending outwardly from the inner edge thereof, there being a corresponding series of radial notches extending inwardly from the outer edge thereof, means for holding said plates in parallel coaxial relation with corresponding notches in alignment, a plurality of expanding pieces having outer

edges normally flush with the outer edges of the end plates and inner edges normally within the inner edges of the end plates, each said expanding piece having a pair of lugs on each end entering a pair of notches in said end plates, the distance between the lugs of each pair being greater than the distance between the notches of each pair, and means for resiliently holding said expanding pieces in their inner position.

In testimony whereof I have affixed my signature.

GUSTAVE ANDERSON.
